(57) **CLAIM**

The ornamental design for ear bud adapter, as shown and described.

DESCRIPTION

FIG. 1 is a perspective view of the ear bud adapter, in accordance with our new design;

FIG. 2 is a right-side elevation view thereof;

FIG. 3 is a left-side elevation view thereof;

FIG. 4 is a front elevation view thereof;

FIG. 5 is rear elevation view thereof;

FIG. 6 is top plan view thereof; and,

FIG. 7 is bottom plan view thereof.

The designation S5 visible in the Figures (e.g., FIG. 3, 7) is not part of the claimed design. The designation L in a circle visible in the Figures (e.g. FIG. 3, 5, 6) is not part of the claimed design.

The broken lines form no part of the claimed design.
